TOBACCO PIPE AND CIGARETTE HOLDER

Rufus E. Barry, Chickasha, Okla.

Application March 24, 1950, Serial No. 151,780

3 Claims. (Cl. 131—213)

1

The invention relates to tobacco pipes and cigarette holders. A number of improvements have been devised for cooling the smoke and eliminating impurities thereof by lengthening the smoke passage through the medium of a multiple reverting smoke passage.

An object of the invention is to provide an improved tobacco pipe and cigarette holder of this general description.

The invention consists in the novel construction and combinations of parts as hereinafter set forth in the claims.

In the accompanying drawings,

Figure 1 is a central longitudinal section of the pipe, some parts being in full lines and broken away.

Figure 2 is a detail perspective view of the stem section and the adjacent portion of the bit section separated from each other.

Figure 3 is a section on the line 3—3, Figure 1.

Figure 4 is a detail end view of the stem section, taken from the forward end thereof.

Figure 5 is a detail end view of the stem section taken from the rear end thereof.

Figure 6 is a diagrammatic view of the reverting smoke passage.

In these drawings, the numeral 1 designates the bowl section of the pipe, having a stub stem portion 1' the free end of which is provided with a cylindrical socket 2 and a central concentric reduced cylindrical socket 3 communicating with socket 2.

The stem proper of the pipe is provided at the bowl end thereof with a reduced cylindrical tenon 4 having a slip joint connection with the outer portion of socket 2 to leave the inner portion of socket 2 vacant. Tenon 4 has a central reduced cylindrical concentric tenon 5 having a slip joint connection with the outer portion of socket 3 to leave the inner portion of socket 3 vacant. The result is an annular smoke passage 6 surrounding tenon 5 and a smoke passage 7 between the end walls of tenon 5 and socket 3.

The stem proper of the pipe is provided at the bit end thereof with a cylindrical socket 8 and a central concentric reduced cylindrical socket 8' communicating with socket 8. The forward end of the bit or mouth piece 10 is provided with a reduced cylindrical tenon 11 which has a slip joint connection with socket 8. Tenon 11 is provided with a further reduced concentric tenon 11' which has a slip joint connection with socket 8'.

The smoke travels from the bottom of the bowl, through a passage 13 in stub stem portion 1' to

5 annular passage 6; thence from annular passage 6 rearwardly through a longitudinal passage 14 which extends in a straight line within the stem proper. Passage 14 communicates rearwardly with a transverse passage 15 leading to a forwardly extending longitudinal passage 16 which also extends in a straight line within the stem proper. Transverse passage 15 is located in the end wall of socket 8 and is completed by the end 10 wall of tenon 11. Passage 16 communicates forwardly with a transverse passage 17 located in the cylindrical wall of tenon 4 and leading to a rearwardly extending longitudinal passage 18 which also extends in a straight line within the stem proper. Transverse passage 17 is completed by the cylindrical wall of socket 2 with which tenon 4 engages. Passage 18 communicates rearwardly with a transverse passage 19 leading to a forwardly extending longitudinal 15 passage 16' which also extends in a straight line within the stem proper. Passage 16' communicates forwardly with a transverse passage 17' located in the cylindrical wall of tenon 4 and leading to a rearwardly extending longitudinal 20 passage 18' which also extends in a straight line within the stem proper. Transverse passage 17' is completed by the cylindrical wall of socket 2 with which tenon 4 engages. Passage 18' communicates rearwardly with a transverse passage 19' leading to a forwardly extending longitudinal 25 passage 20 which also extends in a straight line within the stem proper. Transverse passages 19 and 19' are located in the end wall of socket 8 and are completed by the end wall of tenon 11. Passage 20 is extended forwardly through tenon 30 5 into communication with passage 7, into which passage 7 also opens the forward end of a rearwardly extending longitudinal passage 21 also extending in a straight line within the stem proper.

40 The bit or mouth piece 10 has a smoke passage 22 extending through its tenons 11 and 11' and connecting up with passage 21.

45 Thus the pipe is provided with a multiple reverting smoke passage comprising longitudinal passages 14, 16, 16', 18, 18', 20 and 21 which all respectively extend in a straight line within the stem proper and may be readily cleaned by running a pipe cleaner therethrough upon pulling the 50 sections of the pipe apart at the slip joint connections thereof. Upon pulling the sections of the pipe apart, the transverse passages 15, 19, 19', 17 and 17', and the sockets 2 and 3 are exposed and may be readily cleaned.

55 Since socket 3 is reduced in diameter with re-

spect to socket 2, and tenon 5 reduced in diameter with respect to tenon 4, the above construction constitutes a stepped socket and stepped tenon slip joint connection. Similarly, the stepped construction applies to the stepped sockets 8, 8' and stepped tenons 11, 11', respectively.

The slip joint connections of the pipe sections facilitate the disconnection and connection of the pipe sections and having smooth walls are themselves readily cleaned.

The stem section of the pipe and its smoke passages or channels may vary in length in accordance with the size and shape of different kinds or styles of pipes.

I claim:

1. A tobacco pipe, comprising three separable sections, namely a bowl section, a stem section and a bit section having a stepped socket and a stepped tenon slip joint connection with one another, each stepped tenon slip joint connection comprising a large tenon and a reduced smaller tenon, said sections having a multiple reverting smoke passage comprising longitudinal passages located and respectively extending in a straight line within said stem section, connecting passages for said longitudinal passages opening into and accessible upon separation of said slip joint connections, one of said connecting passages comprising an annular passage located in the bowl section between the end of the related larger tenon and the end wall of its socket and surrounding the related smaller tenon, one of said longitudinal passages extending through said related larger tenon into communication with said annular passage, and the bowl section having a passage leading to said annular passage.

2. A tobacco pipe, comprising three separable sections, namely a bowl section, a stem section and a bit section having a stepped socket and a stepped tenon slip joint connection with one another, each stepped tenon slip joint connection comprising a large tenon and a reduced smaller tenon, said sections having a multiple reverting smoke passage comprising longitudinal passages located and respectively extending in a straight line within said stem section, connecting passages for said longitudinal passages opening into and accessible upon separation of said slip joint connections, one of said connecting passages comprising an annular passage located in the bowl section between the end of the related larger tenon and the end wall of its socket and surrounding the related smaller tenon, one of said longitudinal passages extending through said related larger tenon into communication with said annular passage, the bowl section having a passage leading to said annular passage, another of said connecting passages comprising a passage located in the bowl section between the end wall of the related smaller tenon and the end wall of its socket, another of said longitudinal passages at one end extending through both of said related tenons into communication with the passage of the bit section, others of said connecting passages comprising passages located in the peripheral wall of said related larger tenon, and still others of said connecting passages comprising passages located in the end wall of the socket for the larger tenon related to the bit section.

tudinal passages extending through both of said related tenons into communication with the last named connecting passage, and another of said longitudinal passages at one end extending through both of said related tenons into communication with the last named connecting passage and at its other end having communication with the passage of the bit section.

3. A tobacco pipe, comprising three separable sections, namely a bowl section, a stem section and a bit section having a stepped socket and a stepped tenon slip joint connection with one another, each stepped tenon slip joint connection comprising a large tenon and a reduced smaller tenon, said sections having a multiple reverting smoke passage comprising longitudinal passages located and respectively extending in a straight line within said stem section, connecting passages for said longitudinal passages opening into and accessible upon separation of said slip joint connections, one of said connecting passages comprising an annular passage located in the bowl section between the end of the related larger tenon and the end wall of its socket and surrounding the related smaller tenon, one of said longitudinal passages extending through said related larger tenon into communication with said annular passage, the bowl section having a passage leading to said annular passage, another of said connecting passages comprising a passage located in the bowl section between the end wall of the related smaller tenon and the end wall of its socket, another of said longitudinal passages extending through both of said related tenons into communication with the last named connecting passage, another of said longitudinal passages at one end extending through both of said related tenons into communication with the passage of the bit section, others of said connecting passages comprising passages located in the peripheral wall of said related larger tenon, and still others of said connecting passages comprising passages located in the end wall of the socket for the larger tenon related to the bit section.
